HIS Attorney

Patented Jan. 22, 1929.

UNITED STATES PATENT OFFICE.

THOMAS J. OLSON, OF NEW ROCKFORD, NORTH DAKOTA.

SAFETY SIGNALING APPARATUS.

Application filed March 2, 1926. Serial No. 31,750.

This invention relates to an improved safety signaling device for use by firemen, mine rescue workers, and others who are at times obliged to enter burning buildings or other places where there is a possibility of becoming imprisoned and endangering their own lives.

When a fireman or other worker is obliged to enter a building or other place that is dangerous he will have some way of signaling his companions in reference to any difficulties he may encounter and with especial reference to informing his companions of his whereabouts, as for instance if he feels that he is about to be overcome by smoke or if he has a gas mask on and cannot return to safety or call to his companions, he will still have presence of mind enough to snap the switch on which will start the bell ringing and which bell is loud enough to notify his companions that he is in distress and the sound of the bell will give his companions an opportunity of locating him and rescuing him from his predicament. The device may also be used by the fireman or other worker in calling to his assistance other help, for instance if a fireman who has entered a building with his mask on in search of people that are overcome or cannot escape and he finds one or more of them and he cannot call to his companions and needs assistance, he can turn on the switch of his distress signal and help that is forthcoming will know where the help is needed and the fireman or worker will have an opportunity to save the lives of the persons he has endeavored to rescue.

It is an object of the present invention to provide such a device of a portable nature and of such size as may be readily carried upon a belt or otherwise by the rescue worker, without in any way hindering his movements. The device is adapted to be so shaped as to conform to the curvature of the body, and will be worn much as the conventional first-aid packet.

A further object of the invention is the provision of a signaling device as above noted, comprising an electric bell and switch mounted within convenient reach of the operator, and batteries for the operation of such bell suitably carried within a waterproof casing.

Another object is the provision of such a device which is extremely simple in construction, strong, durable and highly convenient and effective in use.

Other important objects and advantages of

the invention will be apparent during the course of the following description, reference being had to the accompanying drawings, wherein like numerals are employed to designate like parts throughout.

Referring to the drawings:

Fig. 1 is a perspective view of a signaling device constructed in accordance with the invention, and shown as mounted upon a supporting belt.

Fig. 2 is a face view of the device, the battery compartment shown in section, and,

Fig. 3 is a central, vertical, transverse section of the device.

Referring specifically to the drawings, the numeral 5 designates the base member, of the signal mechanism. As clearly shown, this base member is formed concave upon its rear face, and is adapted to be riveted or otherwise suitably attached to a supporting belt 6. The supporting belt 6 in this instance is of a type worn by rescue workers, and is equipped, (not shown), with the several appurtenances incident to such work. It will be obvious, however, that the device might just as readily be supported by a shoulder harness. The base is adapted to be formed of any suitable material, such as phenolic condensation product, fiber, wood, or other composition material light in weight.

Rigidly mounted upon the face of the base 5 is a rectangular metallic battery casing 7, bolted to base 5, as at 8. As shown in Figs. 2 and 3, this casing is formed open at its bottom, and is adapted to be closed by a door 9, hinged as at 10 to the rear wall of the casing. The casing 7 is adapted to receive and support a pair of electric batteries 11, similar to the conventional "C" battery employed in radio work. The batteries 11 are equipped with the usual flexible connections 12.

A bell 13 is supported upon the face of the base 5, above the battery casing, and a switch 14 is likewise mounted upon the base 5 opposite the bell 13. The switch 14 is of a conventional snap nature.

Means are employed to electrically connect the batteries with the bell and switch, comprising a pair of metallic contact strips 15, 105 suitably supported by and insulated from the door 9. These contacts 15 are adapted to forcibly engage the connection 12 when the door is in the closed position. Insulated wires 16 and 17 are connected with the strips 15, as at 18, and these wires are coiled to permit the swinging of the door. The wire 16 is

suitably passed through the base 5, and has connection with the bell 13, while the wire 17 has like connection with the switch 14. The switch 14 and bell 13 are connected by means 5 of a wire 19. The wires 16, 17 and 19 may be embedded in the material of the base, or the base may be suitably drilled for the passage of such wires. A strip contact member 20 is carried by the door 9, and establishes connection 10 between the plus and minus terminals of the batteries, as shown. The door 9 is suitably, rigidly retained in the closed position by means of a screw 21, although many different means may be employed for holding 15 the door in positive closed position.

In operation, when it is desired to sound the signal, the operator merely reaches to his side and snaps on the switch 14. The bell will then start ringing, and continue to do so 20 until either the switch is again manipulated or the batteries have become exhausted. To renew the batteries, it is only necessary to open the door 9, permitting the batteries to drop out, and insert new batteries. The door 25 is then closed to make the necessary electrical connections.

It will be observed from the foregoing,

that an extremely simple and efficient alarm device has been provided. The parts are few and simple, having no movement to cause 30 wear or become disarranged. The battery casing is effectually waterproof against falling water, and the means for electrically connecting the batteries avoids the necessity of wiring such batteries at assembly. 35

It is to be understood that the invention is not limited to the precise construction set forth but that it includes within its purview whatever changes fairly come within either the terms or the spirit of the appended claim. 40

Having described my invention, what I claim is:

A device of the character described comprising a body encircling member, a base plate supported thereon, said base plate 45 formed concave upon its rear face for conforming to the curvature of the body of the wearer, an electric signaling element supported upon said base, said signaling element comprising a battery, a switch of the fixed 50 position type and an audible signaling member.

In testimony whereof I affix my signature.
THOMAS J. OLSON.
